UNITED STATES PATENT OFFICE.

CHARLES A. HICKSON, OF WESTFIELD, MASSACHUSETTS, ASSIGNOR TO THE FULLER
BRUSH COMPANY, OF HARTFORD, CONNECTICUT, A CORPORATION OF CONNECTI-
CUT.

COLLAPSIBLE RECEPTACLE.

Application filed April 7, 1923. Serial No. 630,492.

My invention relates more especially to the class of receptacles designed for the purpose of being removably supported in elevated positions, and from which the contents, as water, will flow by gravity for various uses, as for bath purposes, and an object of my invention, among others, is to provide a device of this class that may be folded into compact form and that, when unfolded and extended, may be secured in an elevated position in a manner to provide a stable structure for receiving liquids, which liquids may be readily withdrawn therefrom; and a further object of the invention is to provide a device of this class that shall be particularly durable and efficient for the purposes for which it is designed.

One form of receptacle embodying my invention, and in the construction and use of which the objects herein set out, as well as others, may be attained, is illustrated in the accompanying drawings, in which:

Figure 1 is a side view of a receptacle embodying my invention.

Figure 2 is a front view of the same.

Figure 3 is a back view with a portion of the fabric cut away on a plane denoted by the dotted line 3—3 of Figure 4 to show the construction of the lower end of the receptacle.

Figure 4 is a bottom view in section on a plane denoted by the dotted line 4—4 of Figure 3.

My improved container is preferably composed of fabric, as a closely woven canvas or duck, that will hold liquids, this being preferably formed from a single piece of material suitably cut to provide the required shape and that is stitched to produce a structure having, when viewed from the top or bottom, a curved front 5 and a flat back 6 of substantially uniform area in cross section from top to bottom. The top and bottom edges of this container are hemmed to provide pockets or cases 7 to receive the end frames that are provided to maintain the receptacle in a substantially semi-circular form in cross section when arranged for use.

Each of these frames is composed of two pieces, preferably of metal, a front piece 8 and a back piece 9, the former being of semi-circular shape and the latter being

straight. The front piece is bent at one end, as at 10, to extend along the back piece and said front piece is secured to one end of the back piece, as by riveting, the opposite end of said back piece having a similar bent portion 11 extending forwardly along the front piece, which bent portion is secured to the front piece as by riveting, and as shown in Figure 4 of the drawings. Both the top and bottom frames are of similar construction. By thus forming the members of each frame each member may be slipped into its pocket or case 7 by passing the unbent end into the opening at the end of the pocket and then slipping the member into place by an endwise movement, after which the rivets may be applied to secure the ends of the members together. The back piece has a loop 12, preferably composed of metal, in the shape of a small ring, this loop being pivotally secured to the back piece of the upper frame at its lengthwise center.

Collapsible struts 13 are pivotally secured to the top and bottom front pieces near their opposite ends, these struts having hinged joints 14 at about their lengthwise centers, which joints are so constructed that they will "break" in one direction only, preferably toward the front.

A hole is formed in the fabric composing the bottom of the container and a stop-cock 16 is secured in this hole, this stop-cock having a shoulder 17 against which the material of the bottom 15 is securely clamped, as by a nut 18 secured on the inner threaded end of the stop-cock inside of the container. In securing the stop-cock, washers are preferably placed against the inner and outer surfaces of the bottom and against said shoulder and nut. This stop-cock is provided with the usual plug and finger-piece 19 as a means for controlling flow of liquid from the container.

The container forming the subject matter of this application is extremely convenient for use for bath or for other purposes in places where temporary means for containing water are desired, the receptacle being so formed that it will rest squarely against a flat or other straight surface, thereby providing a stable structure that may be secured in an elevated position and from which the contents will flow by gravity. Instances for

such uses occur in rural or other localities not supplied with water systems, and the device will also be found very convenient for use in camps and similar places.

5 In accordance with the provisions of the patent statutes I have described the principles of operation of my invention, together with the device which I now consider to represent the best embodiment thereof; but 10 I desire to have it understood that the device shown is only illustrative and that the invention may be carried out by other means and applied to uses other than those above set out.

15 I claim:—

1. A collapsible receptacle composed of flexible material, pockets in the top and bottom edges of the receptacle, each pocket having an opening thereinto, a frame located in each of said pockets, each frame being composed of two members one of which is adapted to be slid into the pocket in one direction and the other is adapted to be slid into the pocket in another direction, and means for securing the adjacent ends of said members together after being slid within the pockets.
2. A collapsible receptacle composed of flexible material formed in semi-cylindrical shape with a flat back, pockets formed in the bottom and top edges of the receptacle, a

frame located in each of the pockets, each frame being composed of two members, each of which has a bent and unbent end, and means for securing the bent end of each member to the unbent end of the opposite member.

3. A collapsible receptacle composed of flexible material formed in a semi-cylindrical shape, with a flat back, pockets formed in the top and bottom edges of the receptacle, a frame located in each of said pockets, each frame being composed of two members each of which has a bent and unbent end, means for securing the bent end of each member to the unbent end of the opposite member, collapsible struts connecting said frames, and means in the bottom of the receptacle for controlling flow of liquid therefrom.

4. A receptacle composed of flexible material formed in a semi-cylindrical shape, with a flat back, a curved and a straight pocket formed in one end edge of the receptacle, a frame composed of two members, one of which is adapted to be slid into one pocket and the other into the other pocket, and means for securing the adjacent ends of said members together after being slid within the pockets.

CHARLES A. HICKSON.
